UNITED STATES PATENT OFFICE.

CHARLES S. ALTOONIAN, OF PROVIDENCE, RHODE ISLAND.

COMBINED LIFE-PRESERVER AND DIVING-SUIT.

1,233,160.

Specification of Letters Patent. Patented July 10, 1917.

Application filed August 28, 1916. Serial No. 117,337.

To all whom it may concern:

Be it known that I, CHARLES S. ALTOONIAN, a citizen of the United States, residing in the city of Providence, in the county of Providence and State of Rhode Island, have invented certain new and useful Improvements in a Combined Life-Preserver and Diving-Suit, of which the following is a specification.

10 An object of this invention is to provide a combined life preserver and diving suit which shall be simple in construction, easily applied in use and *in situ* will be thoroughly effective in supporting the weight of a human body in the water, and when necessity compels may be brought to a condition in which the user will be effectively guarded against any danger of drowning under any but very exceptional circumstances.

20 A further object is to provide a diving suit which shall be simple in construction and easily applied to use, and which requires no connection with the surface while the wearer is under the water, as the diver is provided with the necessary supply of air and is as free under the water as a fish, his movements being in no way interfered with.

The life savers could use this invention to save the lives of drowning persons without any danger to themselves. With the above and other objects in view, as will appear as the nature of the invention is better understood, the same could be used in case of fires, as the firemen could use this to protect their bodies from the heat and from the smoke while on duty, and also people who, caught in a fire could safely escape by means of this invention; an invention that will be very useful on land and on sea, as being light and easy to use.

The invention is embodied in the specific construction and combination of parts hereinafter described, and illustrated in the accompanying drawings, in which:

45 Figure 1 is a face view of the double-walled cloth trousers forming part of the suit.

Fig. 2 is a top view of the trousers.

50 Fig. 3 is a face view of the double-walled cloth helmet.

Fig. 4 includes a side and plan view of a rubber or wooden perforated plug through which rubber tubes pass, as shown in Fig. 10.

Fig. 5 is a face view of rubber trousers

adapted to be worn over the double-walled cloth trousers.

Fig. 6 is a face view of a rubber helmet adapted to be worn over the double-walled cloth helmet.

Fig. 7 is a side view of a sheet-metal can- 60 teen or holder for the diver's air-supply.

Fig. 8 is a face view of the invention complete.

Fig. 9 is a top or plan of the double-walled cloth trousers and rubber trousers. 65

Fig. 10 is a horizontal section on line 10—10 of Fig. 8.

The invention comprises double-walled cloth trousers shown in Figs. 1 and 2, a double-walled helmet shown in Fig. 3, rubber trousers shown in Fig. 5, and a rubber helmet or cover shown in Fig. 6, all of which parts are assembled in Fig. 8.

The cloth trousers and cloth helmet may be made of any suitable material, such as 75 bleached or unbleached bed-sheeting, which, when dampened or soaked in water, becomes air-proof in water, and, also water-proof as long as the garment is filled with air.

As seen in Figs. 1 and 2, double-walled 80 trousers have drawstrings 1 at the top and drawstrings 2 at the bottom of the leg portions. It is apparent these means enable the trousers to be secured water-tight around the body and legs of the wearer.

85 Perforated rubber plates or disks 3 and 4 are cemented to the trousers, and soft-rubber tubes 5 are inserted through them and provided with mouth-pieces 6, for use in inflating the trousers. The mouth-pieces 90 are screwed on the tubes, so that they may be readily attached or removed, as conditions require.

In Fig. 2 the letters L L indicate the leg extensions of the double-walled trousers. 95 Before putting on the latter, they are first soaked or dampened and then drawn on and after the drawstrings 1 and 2 have been tied tightly the garment is inflated by blowing into the mouth piece 6 whereby the outer 100 wall of the trousers is suitably distended.

The double-walled head cover or helmet shown in Fig. 3 is provided at the bottom with drawstrings 7 and at the outer ends of the sleeves with drawstrings 8. In Fig. 105 3, numeral 9 indicates a drawstring applied to a mouth hole 10, which is for use in respiration.

The numeral 11 in same figure indicates a perforated disk secured on the side of the helmet, through which a flexible rubber tube 12 provided with a mouth piece 13 is inserted.

In practice this mouth piece is provided with a valve (not shown), which seats outward. 14 indicates peep holes provided with protecting eye glasses. The numeral 10 22, Fig. 6, indicates eye glasses in the helmet coincident with the peep holes 14 in the inner helmet.

The helmet is applied to the person of the wearer in an obvious manner, and every 15 draw string save 9, is drawn tightly.

In practice, in using the apparatus as a life preserver, the wearer provides himself with rubber gloves and with rubber boots for his feet, and in such case the draw 20 strings of the sleeves of the helmet and the drawstrings of the legs of the trousers are securely tied, so that the wearer's hands and feet will be inside of the apparatus and thus protect him from dampness and cold.

25 When the wearer is out of the water air is discharged from the apparatus by pressing inward the pins (not shown) of the valves of mouth pieces 6 and 13. Whether the apparatus be used as a life preserver or 30 diving suit, a drawstring 20 is tied around the body under the arm pits, as shown in Fig. 8.

In putting on the rubber trousers shown in Fig. 5, flexible rubber tubes 5 are passed 35 through holes 17 and secured. Then the rubber helmet, Fig. 6, is put on and flexible tubes having mouth pieces 6 are inserted through the holes 21 Fig. 6, and also pass through the holes in the wooden blocks 10^a 40 see Fig. 4. Next, bring the mouth piece holder into the mouth hole 10 Fig. 3, and securely tie the drawstrings 9. The wearer of the suit should then try the mouth pieces 6 and 13 to ascertain if he can breathe 45 freely; next, the air holder or canteen shown in Fig. 7 is strapped over the back of the wearer or secured by draw strings.

Upon going into the water, the wearer uses the hand bicycle pump 16 shown in 50 Figs. 5 and 8, and pumps in a quantity of water in order to sink as far as he desires. He stops pumping and unscrews the helmet cap 23 shown in Figs. 6 and 8, to allow water to fill up around the head of the wearer, 55 and also fill the sleeve. This aids in sinking quickly and saves time. The air in the trousers suffices to float the wearer. The water entering the suit serves as a weight to cause sinking, and even if this latter compresses the air a little it does not prevent breathing or floating again when the wearer wishes to come up, which occurs as soon as he unties the draw strings 15 and 20. 60 As shown in Figs. 1 and 2, only the tube 5 which is on the right and connects with

the trousers or inner wall at 4 is used for inflation, and the other or left tube which connects at 3, is used for foul or used air while the wearer is under water.

It must be understood that the wearer 70 using fresh air by means of the right-hand tube 5, 6, 4 (Figs. 1 and 2), throws the used or foul air into the empty chamber by means of the left hand tube 5, 6, 2, so the wearer has the same air about him all the 75 time while even in the water.

After the diver has used all the fresh air provided by the mouth piece 6, he must shut off the tap 28, which is located directly under the fork of the flexible rubber tube 5, so see Fig. 8. He then turns the tap 27 Fig. 8, and the tap 25, forming an attachment of the canteen, Fig. 7. The air in the holder or canteen, Fig. 7, is highly compressed, say 25 or 35 atmospheres, so that 85 when turned on the air will force itself into the flexible rubber tube 5, Fig. 8. Said tube being connected with the air chamber, must be inflated with care so as to conserve and supply fresh air and not overflow the 90 exhaust chamber. It must be understood that the diver must not use the air within the double cloth helmet, Fig. 3, through the mouth piece 13, for if he empties the fresh air from the helmet, he has no means of 95 refilling it under water.

After using all the fresh air available by parts 6, 5, 4, and the canteen the diver is obliged to come up by using mouth piece 13 of the helmet, which will not take too 100 much fresh air out of the helmet. When the diver wishes to come up he must let the water run off by untying the drawstrings 15 of the legs of the rubber trousers Fig. 5, and must also untie the drawstrings 105 20 of the rubber helmet Fig. 6, and must raise his arms at the same time over his head, in order to let the water run out of the sleeves. Then by springing upward he rises like a balloon to the surface of the 110 water. The diver can put his hands under the rubber helmet, Fig. 6, and through the drawstrings 20 under the arm pits, which strings are already untied. He then unties the drawstrings 9 of the mouth hole 10, and pulls out of place the wood or rubber block 10^a, in order to get fresh air. It is to be understood that if the diver desires to go down again, he must empty all the used air 115 by pressing the pins of mouth pieces 6 and 13 without taking off the apparatus.

Recapitulating the foregoing in part, after the diver has donned the complete suit shown in Fig. 8, and has inflated the double-walled cloth helmet and trousers, and adjusted the air canteen, knapsack, or air holder shown in Fig. 7, he should see if he can breathe freely. Next, after entering the water, he first unscrews the cap 23 of the rubber helmet, and then uses the hand 120

pump 16 (Figs. 5 and 8) in order to force 15
in water enough to cause it to sink as far
as he desires. When he stops pumping,
he screws on the helmet cap 23 in order to
5 shut off connection with the surrounding
body of water, and this makes a double
cushion of air and water around the wear-
er's head. Then the diver breathes fresh
air by the right tube 5, 6, 4, and blows the
10 used or foul air into the empty chamber
by the left tube 5, 6, 3.

In using the apparatus in protection of
firemen the operation is substantially the
same as for use of the apparatus by a diver.

I claim:

In a combined life preserver and diving
suit, a pair of double-wall cloth trousers,
and a double-wall cloth helmet, means for
inflating the same, in combination with rub-
ber trousers, and a rubber helmet adapted 20
to be worn over the first-named trousers and
helmet, as described.

In testimony whereof I affix my signa-
ture in presence of two witnesses.

CHARLES S. ALTOONIAN.
